UNITED STATES PATENT OFFICE.

CHARLES W. HUBBARD, OF WESTON, MASSACHUSETTS.

TWISTING MACHINE.

Application filed March 31, 1920, Serial No. 370,260. Renewed September 7, 1922. Serial No. 586,802.

To all whom it may concern:

Be it known that I, CHARLES W. HUBBARD, a citizen of the United States, residing at Weston, county of Middlesex, State of 5 Massachusetts, have invented an Improvement in Twisting Machines, of which the following description, in connection with the accompanying drawing, is a specification, like characters on the drawing representing like parts.

This invention relates to twisting machines for twisting yarn and particularly to that type of twisting machine which is adapted to support and rotate a yarn mass 15 and twist said yarn as it is withdrawn from the mass. The apparatus is adapted to handle yarn to be twisted which is laid or wound in a yarn mass after the manner described in my Patents No. 1,201,049, October 20, 1916, No. 1,232,686, July 10, 1917, and No. 1,258,411, March 5, 1918, and is constructed so that it can be used in connection with a polisher, beaming machine, or other form of winder to deliver twisted 25 yarn to such other machine for some further treatment.

The object of the invention is to provide an improved twisting apparatus of this type which is simple in its construction and which 30 has novel features all as will be more fully hereinafter set forth.

In order to give an understanding of my invention, I have illustrated in the drawings a selected embodiment thereof which will 35 now be described, after which the novel features will be pointed out in the appended claims.

In the drawings, Fig. 1 is a vertical sectional view of a twisting apparatus embodying my invention;

Fig. 2 is an enlarged section on the line 2—2, Fig. 1;

Fig. 3 is an enlarged section on the line 3—3, Fig. 1.

1 indicates a yarn mass containing the 45 yarn 2 to be twisted. This yarn mass is wound after the manner described in my above-mentioned patents so that the yarn 2 may be withdrawn from one end thereof in the direction of the axis of the yarn mass.

The yarn mass is contained in a yarn container 3 which is herein shown as in the form of a tubular can and which is of the type which could be used in connection 50 with the winding apparatus described in

my above-mentioned patents to receive the yarn as it is wound. This yarn container 3 is supported for rotative movement about its vertical axis on a step bearing 4. The twisting of the yarn 2 is accomplished by 60 rotating the yarn container 3 with its yarn mass 1 while the yarn is being withdrawn therefrom. This rotation of the yarn receiver is accomplished by means of a driving member comprising a hollow shaft or 65 sleeve 5 rotatably mounted in bearings 6 and adapted to be rotated by means of a driving pulley 7 fast thereon. This hollow shaft 5 has at its lower end a head 8 to which the upper end of the container 3 may 70 be detachably secured. The upper end of the container is shown as having a ring or flange 9 thereon, and the head 8 is cap-shaped to fit over the ring 9. Said head may be locked to the ring so as to transmit 75 rotative motion thereto by any suitable locking device. As herein shown, the ring 9 has a projection 10 thereon, adapted to enter a notch 11 in the cap. The yarn 2 which is to be twisted is withdrawn from 80 the yarn mass through the hollow shaft 5, said shaft having a delivery opening 111 at its outer end. The yarn may be delivered to any suitable machine which is constructed to give the yarn the desired further treatment. Such other machine may be in the 85 form of a polisher or beaming machine, or a winder adapted to wind the twisted yarn into another yarn mass.

I have not shown herein any complete machine for subsequently treating the yarn, but have merely illustrated two feed rolls 12 which will positively withdraw the yarn from the twisting apparatus and which may be part of, or considered as part of, the machine for giving the yarn subsequent treatment.

The rotation of the yarn receiver while the yarn is being withdrawn therefrom will, of course, twist the yarn between the 100 rolls 12 and the yarn mass, and the amount of twist which is put into the yarn will depend upon the relation between the speed of rotation and the speed of the feed rolls 12.

In order to hold the yarn mass in shape during the rapid rotation of the yarn receiver, I employ a presser-plate 13 which is adapted to rest on the yarn mass and is formed with a central delivery opening 14 110

through which the yarn is delivered. This presser plate is connected to a yarn-guiding tube 15 which extends through the head 8 and into the hollow shaft 5. The yarn-guiding tube 15 is capable of movement axially of the shaft 5, but is connected thereto so as to rotate therewith. This is herein accomplished by providing the shaft 5 with a slot 16 which extends longitudinally 5 through which the yarn is delivered. This presser plate is connected to a yarn-guiding tube 15 which extends through the head 8 and into the hollow shaft 5. The yarn-guiding tube 15 is capable of movement axially of the shaft 5, but is connected thereto so as to rotate therewith. This is herein accomplished by providing the shaft 5 with a slot 16 which extends longitudinally 10 thereof and which receives a projection 17 extending from the yarn-guiding tube 15. The outer end of this projection is connected to a ring 18 which surrounds the shaft 5 and is slidably thereon.

15 The pressure of the presser plate on the yarn mass is that due to the weight of said plate and the weight of the yarn-guiding tube 15, this pressure being sufficient to hold the upper layers of yarn in position as 15 the yarn is withdrawn. I have herein shown the presser-plate as yieldingly connected to the yarn-guiding tube so that the pressure on the yarn mass is a yielding one. For this purpose, said plate is provided 20 with the sleeve 19 into which the lower end of the yarn-guiding tube extends, said sleeve having a slot 20 to receive a pin 21 extending from the yarn-guiding tube. The yarn-guiding tube is also provided with a shoulder 22 against which abuts a coiled spring 23 that surrounds the lower end of the yarn-guiding tube, the lower end of the spring resting against a flange 24 formed on the presser plate circumjacent the opening 14. The presser-plate will thus have a 25 yielding pressure on the yarn mass which will allow it to yield if necessary to permit the free and ready withdrawal of the yarn.

The step bearing on which the yarn container is supported is arranged to be moved vertically. It is shown in Fig. 1 in its elevated operative position which it has when the yarn receiver is operatively connected to the driving member. By lowering the bearing 30 the yarn receiver can be withdrawn or separated from the head 8 of the driving member, thus permitting it to be removed when empty for the purpose of replacing it by a filled yarn receiver having untwisted 35 yarn therein. The step bearing may be raised or lowered in any suitable way without departing from the invention. I have herein shown it in the form of a plunger movable vertically in a cylinder 25 which 40 is arranged to receive air under pressure through a pipe 26. When the cylinder is filled with compressed air the step bearing will be held in its raised position but by withdrawing the air the bearing will be 45 lowered sufficiently to permit the yarn container to be separated from the head 8.

When the yarn container is to be removed from the apparatus, the presser-plate will be raised up against the head 8. This 50 can be done by the operator grasping the ring 18 and moving it upwardly on the shaft 5. The ring with the presser-plate suspended therefrom may be held in the raised position by suitable hooks or catches 27 which are secured to the upper bearing 6. 55 Various changes may be made in the constructional details of the device without departing in any way from the invention covered by the appended claims. 75

I claim:

1. In a twisting apparatus, the combination with a yarn receiver, of a driving member in the form of a hollow shaft connected thereto, a yarn-guiding tube extending into and movable axially of the hollow shaft, a presser-plate carried by said tube and adapted to rest on the yarn mass, means for rotating the driving member with its attached container, and a driving connection between said shaft and yarn-guiding tube. 80
2. In a twisting apparatus, the combination with a yarn container containing the yarn to be twisted, of a hollow driving shaft extending axially of said container, means connecting said container to said shaft, a yarn-guiding tube extending into and movable axially of the hollow shaft, a presser-plate yieldingly carried by said tube at its lower end and adapted to rest on the yarn mass in the yarn container, means for rotating the driving member, and means to rotate the yarn tube from the driving shaft while permitting longitudinal movement of said tube relative to the shaft. 85
3. In a twisting apparatus, the combination with a rotatable yarn container, of a driving shaft situated axially thereof and connected thereto, said shaft having a yarn delivery passage communicating with the yarn container, means to rotate said shaft, a presser plate movable axially of the yarn container and adapted to rest on the yarn mass therein, said plate having a central yarn delivery opening, and means connecting said plate to said shaft. 90
4. In a twisting apparatus, the combination with a rotatable yarn container, of a driving shaft situated axially thereof and connected thereto, said shaft having a yarn delivery passage communicating with the yarn container, a spring-pressed presser plate movable axially of the yarn container and adapted to rest on the yarn mass, said plate having a central yarn-delivery opening, means to rotate said shaft, and a driving connection between said shaft and said presser plate. 95
5. In a twisting apparatus, the combination with a yarn container, of a hollow driving shaft situated axially thereof and connected thereto, a yarn-guiding tube extending into and movable axially of the hollow shaft, said shaft having a longitudinal slot, a projection extending from said yarn-guiding tube and operating in said 100

slot, and a presser plate carried by the lower end of said tube and adapted to rest on the yarn mass in the yarn container.

6. In a twisting apparatus, the combination with a yarn container, of a hollow driving shaft situated axially thereof and connected thereto, a yarn-guiding tube extending into and movable axially of the hollow shaft, said shaft having a longitudinal slot,

a projection extending from said yarn-guiding tube and operating in said slot, a ring secured to said projection and encircling the tube, and a presser plate yieldingly connected to the lower end of the yarn-guiding tube and adapted to rest on the yarn mass.

In testimony whereof, I have signed my name to this specification.

CHARLES W. HUBBARD.
